UNITED STATES PATENT OFFICE.

MICHEL D. LUEHRS, OF CLEVELAND, OHIO.

BOLT-CUTTER HEAD.

SPECIFICATION forming part of Letters Patent No. 324,946, dated August 25, 1885.

Application filed April 2, 1884. (No model.)

To all whom it may concern:

Be it known that I, MICHEL D. LUEHRS, a citizen of the United States, residing at Cleveland, in the county of Cuyahoga and State of Ohio, have invented certain new and useful Improvements in Bolt-Cutter Heads; and I do hereby declare the following to be a description of the same, and of the manner of constructing and using the invention, in such full, clear, concise, and exact terms as to enable any person skilled in the art to which it appertains to construct and use the same, reference being had to the accompanying drawings, forming a part of the specification, the principle of the invention being herein explained and the best mode in which I have contemplated applying that principle, so as to distinguish it from other inventions.

One end in view in devising this invention was to provide a construction of few parts. A further end was to make the construction without a ring which engages directly with the dies, said construction being also adapted for the use of dies varying in length to any desired extent. An additional object was to positively retract the dies from operative position by a working-ring located outside of the plane of the dies. Still another object was to lock the dies in operative position by said working-ring; and, lastly, I desired to obtain a radial adjustment of the dies in a quick and accurate manner.

With these several ends in view my invention consists of principles of construction and operation capable of being carried out in different mechanical ways, certain ones of which are illustrated in the drawings, as follows:

Figure 1 is a longitudinal horizontal section of one form of the invention. Fig. 2 is a front elevation of the same. Fig. 3 is a plan of a second form of the invention, the top arm thereof being broken away. Fig. 4 is a longitudinal central section of the double ring shown in the preceding view. Fig. 5 is a front elevation of the double ring. Fig. 6 is a plan of a third form of the invention. Fig. 7 is a front elevation of same. Fig. 8 is a plan of the upper part of the bipartite ring. Fig. 9 is an elevation of the part shown in preceding view. Fig. 10 is a side view, Fig. 11 an end view, and Fig. 12 a horizontal section, of

a modified form of die-holder, which may be used in substitution for the die-holders shown in Figs. 1 and 2, and which, like them, is adapted to dies of any and varying length. 55 Fig. 13 is a detail section of a modified form of die-holder according to which the rocking levers are detachably connected to said die-holder. Fig. 14 is a detail of the rocking lever of the preceding view. Fig. 15 is a detail side view representing a die directly connected to its rocking lever. Fig. 16 is a front elevation of the preceding view.

The construction represented in the first two figures shows four rocking levers, A, respectively working in openings formed at equidistant quadrant-points of the barrel. Each lever has its forward extremity connected directly to a die-holder, a, and they are all operated by a bipartite ring adapted to have 70 sliding movement longitudinally on the barrel, said ring being located outside of the plane in which the dies A' are located. One section, C, of this ring is loosely fitted to have reciprocating revolving movement within the 75 other section, D. It is provided with set-bolt a', rigid therewith, and working in peripheral slot b, formed in section D. A nut, c, is threaded on the extremity of the bolt, which projects from the slot, and thus clamps the 80 revolving section at any desired adjustment to the rectilinear sliding section. To aid in the rapidity and accuracy of such adjustment, a scale, d, and index-finger e are provided, respectively, on the two sections. The object 85 of this reciprocal revolution is to cause the dies to be at any desired distance from the axis of the head when clamped in operative position as may be required by the diameter of the article to be threaded. To this end I form a series of 90 cams on the forward portion of the inner periphery of the revolving ring-section; and to obviate binding of the ring, and secure nicely of operation of the parts, I form a companion series of cams on the rear portion of the ring 95 periphery. A further consideration is to lock the ring respectively in its forward and rear positions, the locking in forward position being the more important point of the two, in order to maintain the dies in position during 100 the operation of cutting the bolt. To carry out this threefold consideration, the inner pe-

riphery of the revolving section C has its forward and rear portions, respectively, provided with a series of four inclined cams, h h' . (See Figs. 4 and 5.) Each series has its four cams 5 inclined in the same circular direction considered above; but the cams of the front series, h , incline in opposite circular direction to the cams h' of the rear series. In the rear of each cam of the front series there is a correspondingly-shaped but oppositely-inclined cam in the rear series. These two series of cams engage, respectively, with flat surfaces 10 l and k , formed on the front and rear ends of each of the rocking levers. By the engagement 15 of these flat bearings with the ring said levers are locked, and accidental movement is impossible. The ring is prevented from binding in this lever-locking by the opposite inclinations of the two series of cams. 20 Section D of the bipartite ring is provided with a pin, f , fitting in a guide-slot, g , formed longitudinally in the barrel, whereby said section is maintained in rectilinear movement as it slides to and fro on the barrel. Any suitable 25 means may be employed for operating the ring in this rectilinear movement.

The bipartite ring is shown in different forms of mechanical detail respectively in the different heads illustrated in Figs. 1 and 3, while 30 in the head illustrated in Fig. 6 I have shown a single ring adapted to have rectilinear sliding movement on the barrel, no provision being made therein for adjustment of the dies, as in the two other heads.

Fig. 13 represents a die-holder, E, having an opening in which is detachably fitted the shank m of a rocking lever. Figs. 15 and 16 represent a rocking lever directly connected to the die by a pin.

From the foregoing it will be observed that 40 my invention is subdivided into several distinct principles of construction not dependent upon each other, one or more of said principles being adapted to be incorporated in the same machine as desired.

Simplicity of construction and minimum 45 number of working parts are features found alike in all the various forms shown. The rocking levers are connected directly to the dies or die holders, and are operated by a working-ring located outside of the plane of the said dies. Steel of any and varying length may be employed as dies when so desired, and the working-ring is positively actuated in movements 50 both forward and return. The cam-ring section permits of rapid and exact change of parts, so as to cause the dies, when clamped in operative position, to be all at a greater or less distance from a common center, and the flat 55 bearings between the ring and levers insure the latter against the possibility of change of position until the ring releases them.

Other forms of embodying and using the 60 principle of my invention may be employed in substitution for the specific forms herein shown. It will therefore be understood that omissions, substitutions, and changes may be

made as regards the forms and parts herein set forth, provided the principles of construction embraced in the following claims are retained and employed.

I therefore particularly point out and distinctly claim as my invention—

1. In a bolt-cutter head, the combination, 75 with a rocking lever having its forward extremity directly and positively secured to a die or die-holder, of a ring located outside and rearward of the plane of the die, said ring having engagement with said lever forward of its pivotal plane to move its forward extremity 80 toward the head-axis, whereby the die is actuated in a corresponding movement directly by the lever, substantially as set forth.

2. In a bolt-cutter head, the combination, 85 with a rocking lever having its forward extremity directly and positively secured to a die or die-holder, of a ring located outside and rearward of the plane of the die, said ring engaging with the lever forward of its pivotal plane to move the die toward the head-axis, 90 and engaging with said lever rearward of its pivotal line to move the die from the head-axis, substantially as set forth.

3. In a bolt-cutter head, the combination, 95 with rocking lever A, of ring C, provided with inner peripheral cam, h , on its forward portion, engaging with said lever forward of its pivotal point, substantially as set forth.

4. In a bolt-cutter head, the combination, with ring C, having the two series of inner peripheral cams, h and h' , respectively formed in its forward and rear portions, of rocking levers A, respectively adapted to engage at points forward of their fulcrums with said cam series h , and at points rearward of their fulcrums 105 with said cam series h' , substantially as set forth.

5. In a bolt-cutter head, the combination, 110 with rocking levers A, respectively provided with flat bearings l , located forward of their pivotal points, of ring C, having the series of inner peripheral cams, h , formed on its forward portion, said cams having engagement with said flat bearings to lock the levers against accidental movement tending to move 115 their forward extremities from the head-axis, substantially as set forth.

6. In a bolt-cutter head, the combination, 120 with ring C, having the series of inner peripheral cams, h' , formed on its rear portion, of curved rocking levers A, respectively provided with flat bearings k rearward of their pivotal points, said ring being located outside and in rear of the plane of the dies, and adapted by the engagement of said parts h' and k to lock 125 the curved levers against accidental movement tending to move their forward extremities toward the axis of the head, substantially as set forth.

7. In a bolt-cutter head made without a ring 130 in the plane of the dies, the combination, with ring C, having the two series of inner peripheral cams, h and h' , respectively formed in its forward and rear portions, of rocking levers

A, having forward and rear flat bearings, *l* and *k*, substantially as set forth.

8. In a bolt-cutter head, the combination, with rocking levers *A*, of ring *D* and ring *C*, 5 adapted to have circular adjustment relative to the latter, both said rings being located outside and in rear of the plane of the dies, said ring *C* having the two series of inner peripheral cams, *h* and *h'*, respectively formed in its forward and rear portions, and respectively engaging with said levers at points forward and rearward of their fulerums, substantially as set forth.

9. In a bolt-cutter head, the combination, 10 with a die and a rocking-lever, of a ring having two peripheral cams, respectively adapt-

ed to engage with said lever at points on opposite sides of an intermediate line passing through the center of movement of the lever, substantially as set forth.

10. In a bolt-cutter head, the combination, 20 with a ring having circular and endwise movements, of a rocking lever having engagement with two cams formed on the inner periphery of the ring, substantially as set forth.

In testimony that I claim the foregoing to be my invention I have hereunto set my hand this 25th day of March, A. D. 1884.

MICHEL D. LUEHRS.
